CLAIM

The ornamental design for a housing for an electronic
push button dialer, as shown and described.

DESCRIPTION

FIG. 1 is a front perspective view of a housing for an
electronic pushbutton dialer showing my new design;
FIG. 2 is a top plan view thereof;

FIG. 3 is a front elevational view thereof;

FIGS. 4 and 5 are respectively right and left side eleva-
tional views thereof;

FIG. 6 is a rear elevational view thereof;

FIG. 7 is a bottom plan view thereof; and

FIG. 8 is a top plan view of a second embodiment
thereof, which has a front elevational view as shown in
FIG. 3, a right side elevation as shown in FIG. 5, a rear
elevation as shown in FIG. 6, and a bottom plan view as
shown in FIG. 7.

FIG. 2
